(57) **CLAIM**

The ornamental design for a vibration and temperature measuring device, as shown and described.

DESCRIPTION

FIG. 1 is a first partial enlarged perspective view of a vibration and temperature measuring device;

FIG. 2 is a second partial enlarged perspective view thereof;

FIG. 3 is a third partial enlarged perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is an enlarged front view of FIG. 4 thereof;

FIG. 11 is an enlarged rear view of FIG. 5 thereof;

FIG. 12 is an enlarged left side view of FIG. 6 thereof; and,

FIG. 13 is an enlarged bottom view of FIG. 9 thereof.

The broken lines depict portions of the vibration and temperature measuring device in which the design is embodied that are not considered part of the claimed design.
